Primary Examiner — S. Bryan Reinholdt, Jr.*Assistant Examiner* — Andrew D Golson(74) *Attorney, Agent, or Firm* — Meunier Carlin & Curfman LLC(57) **CLAIM**

The ornamental design for a sheet pile connector, as shown and described.

DESCRIPTION

FIG. 1 is a front perspective view of a sheet pile connector showing my new design; and,

FIG. 2 is a side view thereof.

The sheet pile connector includes a symbolic break drawn in dot-dash broken lines. The broken lines depict portions of the sheet pile connector that form no part of the claimed design. The dot-dash broken break lines and the area between the break lines form no part of the claimed design.
